UNITED STATES PATENT OFFICE

MARK H. MARTIN, OF BALTIMORE, MARYLAND, ASSIGNOR TO THE SYMINGTON COMPANY, OF NEW YORK, N. Y., A CORPORATION OF MARYLAND

CAST-STEEL SIDE FRAME

Application filed July 18, 1925. Serial No. 44,566.

This invention relates to side frames for railway car trucks and more particularly to frames having journal boxes integral therewith.

5 The principal object of my invention, generally considered, is the provision of cast integral side frames in which the various members thereof are so designed with respect to the cross-section and so arranged 10 with respect to each other that great strength, compared with the weight thereof, is secured.

An object of my invention is the provision 15 of a cast side frame for railway trucks in which the various members thereof are so designed and the cross-sections thereof are so varied that the most economical cross-sections are employed in the various positions on the frame and for that purpose the cross- 20 sections of one or more of the members thereof varies radically between the ends thereof whereby valuable results such as lightening the weight of the frame without sacrificing the necessary strength thereof, are secured.

25 Another object of my invention is the provision of a cast side frame for railway car trucks formed with a compression member, the intermediate portion of which is channel-shape and the end portions of which are 30 gradually changed to a T or I shape, a tension member, the central portion of which is box-shape, and the end portions of which are formed as inverted channels with upstanding ribs from the webs thereof, said members 35 being spaced by bolster column or strut portions, merging at their lower ends with the upstanding ribs on the tension member and at their upper ends with intermediate portions of the compression member.

40 A further object of my invention is the provision of a cast side frame for railway car trucks formed with compression, tension and bolster column members, said bolster column members spacing intermediate portions of the compression and tension members and merging therewith, said frame being formed with a bolster opening framed by said members, the compression member above the bolster opening being formed as a channel 45 in cross-section, the tension member beneath

the bolster opening being box-shape in cross-section, the bolster columns being channel-shape in cross-section, said compression member uniting with the tension member and with journal boxes at the ends of the 55 frame, said frame being substantially I-section above the journal boxes, those portions of the tension member diagonally disposed between the journal boxes and the lower corners of the bolster opening being formed 60 as inverted channels with ribs or I sections rising from the backs of the channel webs.

A still further object of my invention is the provision of a cast side frame for railway car trucks formed with compression 65 and tension members and bolster column or strut members spacing intermediate portions thereof, said tension member being formed as a box-section joining the lower portions of the bolster column members 70 and as an inverted channel-section extending diagonally upward from the ends of said box-section, the transverse web of said diagonal portions extending in a straight line from the lower corner of the bolster opening 75 to the corner of the adjacent journal box roof, the depending flanges of the section extending from the box-section beneath the bolster opening to the side walls of the journal boxes, said diagonal tension portions being formed with longitudinal, central rib 80 portions rising from the backs of the transverse web portions thereof, merging with the bolster column portions at their lower ends and with the web of the compression 85 member at their upper ends.

Other objects and advantages of the invention relating to the particular arrangement and construction of the various parts of my improved side frame will become apparent as the description proceeds.

Referring to the drawings illustrating my invention, the scope whereof is defined by the claims:

Figure 1 is a side elevation of a cast side 95 frame for railway car trucks embodying my invention, a portion of said frame being shown in section.

Figure 2 is a plan view of the side frame of Figure 1 shown partly in section on the 100

line 2-2 of Figure 1, and partly broken away.

Figure 3 is a cross-sectional view on the line 3-3 of Figure 1, looking in the direction of the arrows.

5 Figure 4 is a detail cross-sectional view on the line 4-4 of Figure 1.

Figure 5 is a detail cross-sectional view on the line 5-5 of Figure 1.

10 Figure 6 is a similar cross-sectional view on the line 6-6 of Figure 1.

Figure 7 is a partial cross-sectional view on the line 7-7 of Figure 1.

15 Referring to the drawings in detail, in which similar reference characters designate like parts, there is shown a cast side frame 1 which, in the embodiment illustrated, comprises a compression member 2, a tension member 3, bolster column guide or strut members 4, and journal boxes 5. The compression and tension members unite at the ends thereof and are also preferably integral with the journal boxes 5. Intermediate portions of the compression and tension members are 20 spaced by the bolster column members 4 which are shown as integral therewith.

25 The various frame members are formed of varying sectional configuration in order to secure great economy of material without sacrificing requisite strength in the frame. For example, the compression member 2, over the bolster or window opening 6, is formed of inverted U-shape or as a channel with an upper web portion 7 and depending flanged 30 portions 8. The lower edges of said flange portions 8 are preferably beaded or provided with outstanding rib portions 9.

35 After passing outwardly beyond the bolster opening, the cross-section of the compression member changes gradually so that over the journal boxes the section is substantially T or I shape with an upper flange 10 curved downwardly and meeting the roof 11 of the journal box substantially in line 40 with the outer brass lug 12. That is, the upper edge, which changes from a web 7 to a flange 10, slopes from a horizontal to substantially a vertical position where it joins with the journal box 5.

50 The web 13 of the T or I section over the journal boxes merges with the roof 11 of each journal box, as illustrated. During the transition from a channel to an I section the depending flanges 8 of the compression member 55 gradually converge and finally unite to form the web 13, the upper portion or web 7 thereof becoming a flange 10 without other radical change although it may taper slightly toward its ends. The lower edges 9 of the flanges 8 converge along with said flanges at 60 14 and preferably form oppositely directed beads or flanges of the tension member 3, as will hereinafter be more fully described.

65 From the foregoing it will be apparent

that the compression member, in changing from a channel to an I or T section, passes through a stage in which it is substantially a double I section, that is, it has two webs, an integral upper flange and two lower flanges or beads. Where said lower flanges or beads 9 have united to form a single flange 14, said flange is curved downwardly and inwardly to form the upper flange of the diagonal end portions of the tension member 3. Said tension member 3 is continued beneath the bolster opening 6 as a substantially horizontal beam, rectangular or box-shape in cross-section.

70 Adjacent the opposite lower corners of the bolster opening, the lower web 15 of the box-shaped horizontal portion of the tension member 3 is provided with openings which gradually increase or taper in width; the edges of said openings forming inwardly extending tapering flanges 16 on the depending webs or flanges 17 of the tension member. The outer portions of the tension member, that is the portion between each journal box and the adjacent strut, are bent 75 or sloped outwardly and upwardly and the upper web 18 thereof is continued straight to join the journal boxes 5 adjacent the upper inner corners thereof and preferably at the junction of the inner brass lug 19 with the roof 11. It will therefore be apparent that the main portions of the tension member 3 change from box-section to inverted channel-section in passing from that portion beneath the bolster opening 6 to the journal 80 boxes 5.

85 The bolster column portions 4 are formed of substantially U or channel shape in cross-section with web portions 20 forming bolster guides and outwardly extending flanged 90 portions 21 beaded or ribbed at the edges thereof, as indicated at 22. The lower portions of the web 20 are outwardly offset, at 95 23, as is usual, to facilitate the insertion of the bolster, and apertured at 24 for core removal. The flanges 21 adjacent the lower portions thereof are converged toward each other and finally joined at 25 and continued as a single web or flange 26 upstanding and centrally longitudinally disposed along the 100 transverse web 18 of the diagonal portions of the tension member 3. The upper edge of this web or flange 26 is bounded by the flange or bearing 14 continued from the compression member 2.

105 It will thus be apparent that the lower portions of the bolster column members 4 merge with the transverse web 18 of the diagonal portions of the tension member 3 and are continued to form an extension or 110 additional T or I section joined with the inverted channel section thereof. The upper ends of the bolster column members 4 merge with the lower portions of the compression member 2, the webs 20 of said bolster column 115 120

portions being bifurcated adjacent their upper ends and the opposite portions thereof gradually tapering or decreasing in width so as to finally merge with the depending flange 8 of the compression member over the 5 bolster opening.

The flanges 21 of the bolster column portions merge with the flanges 8 of the compression member 2, the beading 9 thereon, however, preferably extending above the upper 10 ends of the bolster column members and merging with the beading 22 at the ends thereof. Said beading 22 at its upper end is preferably curved outwardly and continued 15 around the triangular openings 27 to form an integral framing therearound with the beading 9 and 14.

The upper web 28 of the tension member beneath the bolster opening 6 is preferably formed relatively wide for the accommodation 20 of the bolster springs. A plurality of bosses 29 may also be provided thereon. The portions 30 of the spring seating portion 28, extending beyond the depending web portions 17, are preferably braced with respect thereto by triangular reinforcing webs 31. An aperture 32 may be provided adjacent the central portion of the web 30 for removing the core from the box section therebeneath.

The lower flange portions of the tension member adjacent the lower corners of the window opening 6 are preferably curved outwardly and upwardly, as illustrated, to give adequate strength beneath the window 30 opening corners. The lower edges of the tension member 3 are then continued substantially parallel, but slightly converging with respect to the transverse web 18 thereof, to the vicinity of the adjacent journal box where the depending flange portions 17 are flared downwardly and joined with the journal box inner wall 33, as illustrated.

Triangular reinforcing webs 34 may be provided between the outer edges of the tension member web 18 and the upper inner corners of the journal boxes 5.

Brake hanger brackets 35 may be integrally united with the compression member 2, as illustrated, said brackets, in the present embodiment, being provided with upright web portions 36 merging with the adjacent depending flange 8 of the compression member 2 and upper flange portions 37 gradually increasing in width toward the compression member 2, and finally merging therewith. The lower flange 38 of the brake hanger bracket 35 may be extended and joined with the lower edges or beading 9 of said adjacent flange 8 of the compression member 2.

The compression member 2 is preferably of lighter section than the tension member because it carries less stress than said tension member and the inner flanges of all members are preferably formed thinner than the

corresponding outer flanges thereof. The reason for this difference in flange thickness is that side frames of the present type are cast with the outer or front face on the upper side of the mold, so that when the metal is poured into the mold, the rear portion of the frame is formed first and as the pouring is continued the metal rises and finally forms the front portion. Unless provision is made to take care of the difference in quality between the metal first poured and that subsequently poured, the front and rear flanges will have different strengths per unit area and in service there would be a tendency to stress the outer flanges of the frame to a greater degree in proportion to their strength than the inner flanges. By providing flanges of unequal thicknesses this defect has been obviated so that the side frame is provided with opposite flanges of uniform strength.

In view of the foregoing disclosure it will be appreciated that I have devised an improved form of side frame in which the sections of the various members are varied in shape and strength to efficiently take care of the stresses which they are called upon to bear in service, whereby great economy in design is secured and the weight of the frame reduced without deleteriously decreasing the strength thereof.

Having thus described my invention, I claim:

1. A truck side frame comprising a tension member, a compression member, bolster guide columns interposed between intermediate portions of said members and leaving a bolster opening therebetween, journal boxes at the ends of said frame, the tension member being formed with diagonal end portions having transverse web portions extending below the upper edge thereof from the lower corners of the bolster opening to the roofs of the journal boxes, said web portions being formed with depending flanges extending from beneath the bolster opening to the journal boxes.

2. A truck side frame comprising a tension member, a compression member, bolster guide columns interposed between intermediate portions of said members and leaving a bolster opening therebetween, journal boxes at the ends of said frame, the tension member being formed with diagonal end portions having transverse web portions extending below the upper edge thereof from the lower corners of the bolster opening to the roofs of the journal boxes, said web portions being formed with depending flanges extending from beneath the bolster opening to the journal boxes, the intermediate portion of the tension member beneath the bolster opening being substantially rectangular in cross-section, with the side walls thereof formed as continuations of said depending flanges.

3. A truck side frame comprising a tension member, a compression member, bolster guide columns interposed between intermediate portions of said members and leaving a bolster opening therebetween, journal boxes at the ends of said frame, the tension member being formed with diagonal end portions having transverse web portions extending from the lower corners of the bolster opening to the roofs of the journal boxes, said web portions being formed with depending flanges extending from beneath the bolster opening to the journal boxes, and with upstanding portions merging at their lower ends with the bolster guide columns and at their upper ends with the compression member.

4. A truck side frame comprising a tension member, a compression member, bolster guide columns interposed between intermediate portions of said members and leaving a bolster opening therebetween, journal boxes at the ends of said frame, the tension member being formed with diagonal end portions having transverse web portions extending from the lower corners of the bolster opening to the roofs of the journal boxes, said web portions being formed with depending flanges extending from beneath the bolster opening to the journal boxes and with upstanding central longitudinal web portions, flanged at their upper edges, said web portions being continued at their upper ends as web portions of the compression member and at their lower ends bifurcated and continued as flanges of the bolster columns.

5. A truck side frame comprising a tension member, a compression member, bolster guide columns interposed between intermediate portions of said members and leaving a bolster opening therebetween, journal boxes at the ends of said frame, the tension member being formed with diagonal end portions having transverse web portions extending from the lower corners of the bolster opening to the roofs of the journal boxes, said web portions being formed with depending flanges extending from beneath the bolster opening to the journal boxes, and with upstanding central longitudinal web portions formed with transverse flanges at their upper edges, said flanges being continued at their upper ends as lower flanges of the compression member and at their lower ends bifurcated and continued as beading on the bolster columns.

6. A truck side frame comprising a tension member, a compression member, bolster guide columns interposed between intermediate portions of said members and leaving a bolster opening therebetween, journal boxes at the ends of said frame, the compression member at the intermediate portions thereof over the bolster opening being gen-

erally channel-shape in cross-section, with a transverse web and flanges on either side thereof, said flanges, beyond the bolster opening, gradually converging from the sides of the web and uniting along the full height thereof to form upright web portions over the journal boxes.

7. A truck side frame comprising a tension member, a compression member, bolster guide columns interposed between intermediate portions of said members and leaving a bolster opening therebetween, integral journal boxes at the ends of said frame, the compression member at the portion thereof over the bolster opening being generally channel-shape in section, with a transverse web and depending flanges on either side thereof, said flanges, beyond the bolster opening, gradually converging beneath the web, united to form upright web portions and continued to the journal boxes and as web portions of the tension member.

8. A truck side frame comprising a tension member, a compression member, bolster guide columns interposed between intermediate portions of said members and leaving a bolster opening therebetween, journal boxes at the ends of said frame, the compression member at the portion thereof over the bolster opening being generally channel-shape in section, with a transverse web and depending flanges on either side thereof, said flanges, beyond the bolster opening, gradually converging beneath the web, united to form upright web portions and continued to the journal boxes and as web portions of the tension member, the web of the channel section gradually forming upper flanges on the upright web portions which curve downwardly and unite at their ends with the journal boxes.

9. A truck side frame comprising a tension member, a compression member, bolster guide columns interposed between intermediate portions of said members and leaving a bolster opening therebetween, journal boxes at the ends of said frame, the compression member at the portion thereof over the bolster opening being generally channel-shape in section, with a transverse web and depending flanges on either side thereof, said flanges, beyond the bolster opening, gradually converging beneath the web, united to form upright web portions and continued to the journal boxes and as web portions of the tension member, the lower edges of the channel section being beaded, finally uniting adjacent the ends of the frame, as single flange portions and continued as upper flanges of the tension member.

10. A truck side frame comprising a tension member, a compression member, bolster guide columns interposed between intermediate portions of said members and leaving a bolster opening therebetween, journal boxes

- at the ends of said frame, the tension member being formed with diagonal end portions, inverted channel-shape in cross-section, with an upstanding rib along the upper surface of the transverse channel web, said web extending in a straight line, along each end portion, from a lower corner of the bolster opening to the inner corner of the adjacent journal box roof.
11. A truck side frame comprising a tension member, a compression member, bolster guide columns interposed between intermediate portions of said members and leaving a bolster opening therebetween, journal boxes at the ends of said frame, the tension member being formed with diagonal end portions, inverted channel-shape in cross-section, with an upstanding rib along the upper surface of the transverse channel web, said web extending in a straight line, along each end portion, from a lower corner of the bolster opening to the inner corner of the adjacent journal box roof, joining with said roof adjacent the junction of the inner brass lug therewith.
12. A truck side frame comprising a tension member, a compression member, bolster guide columns interposed between intermediate portions of said members and leaving a bolster opening therebetween, journal boxes at the ends of said frame, the tension member being formed with diagonal end portions, inverted channel-shape in cross-section, with an upstanding rib along the upper surface of the transverse channel web, said web extending in a straight line, along each end portion, from a lower corner of the bolster opening to the inner corner of the adjacent journal box roof, the depending flanges of the channel-section extending from beneath the bolster opening to the outer end of each diagonal portion of the tension member where they are flared downwardly and united with the inner walls of the journal boxes.
13. A truck side frame comprising a tension member and journal boxes integrally connected thereto, the end portions of said tension member being diagonally disposed and comprising an intermediate web portion with upright flanges extending one way and a single upright flange extending the other way therefrom.
14. A truck side frame comprising a tension member formed with a substantially horizontal intermediate portion and diagonally disposed end portions, said end portions being formed with a transverse web from which depend a plurality of flanges and the upper surface of which is formed with a single upstanding flange.
15. A truck side frame comprising a tension member having diagonally disposed end portions, the upper portions of which are formed generally T shape in cross section and the lower portions of which are formed generally channel shape in cross section.
16. A truck side frame comprising a tension member having diagonally disposed end portions formed with a transverse web, the outer edges of which are provided with depending flanges and the intermediate portion of which is formed with an upstanding flange.
17. A truck side frame comprising a compression member, the central portion of which is generally channel shape in cross section and the end portions of which are generally T shape in cross section, said member being formed so that one section gradually merges into the other.
18. A truck side frame comprising a compression member formed with an intermediate portion substantially U shape in cross section, the flanges of the U gradually converging towards the ends of the member to form a single web along the full height of said member, the web of the U being continued to form a flange on the single web portion of the member.
19. In an integral side-frame-journal-box structure for car trucks, a side-frame having a top compression member and a bottom tension member, said frame members being of channel form in the main part of the frame intermediate the journal boxes, and being of I-section at and in the neighborhood of the journal box.
20. In an integral side-frame-journal-box structure for car trucks, a side-frame having a top compression member and a bottom tension member, said two members in the main part of the frame intermediate the journal boxes being of channel form including horizontal webs and vertical flanges, the horizontal web of the top member joining the top of the journal box and the horizontal web of the bottom member joining the inner wall of the journal box, and the vertical flanges of one of said members converging towards each other to join at points spaced inwardly from the journal box in a vertical web which extends from the top wall of said boxes.
21. A side frame comprising a tension member formed with normally vertical flanges connected at their lower edges by a web, said tension member having a central or intermediate horizontal portion, with an upper web extending beyond the sides of the flanges to provide a spring plank seat, and upwardly and outwardly extending end portions, the upper web of said intermediate portion beyond the sides thereof being continued upwardly and outwardly along the end portions below but parallel to the upper edges of said end portions, the lower edge of said tension member where each end portion joins the central or intermediate portion being first concave downwardly and then convex downwardly for maintaining the depth

of the member at said junctions to correspond with the depth of the intermediate portion.

22. A side frame comprising a tension member formed with an intermediate substantially horizontal portion and end portions extending diagonally outward and upward therefrom, bolster guide columns extending upward from the junctions of the end and intermediate portions of said member, said tension member comprising a pair of normally vertical flanges, the lower outline of which is curved first in one direction and then in the other beneath each bolster guide column for maintaining the depth of the tension member to correspond with that of the horizontal portion thereof to beyond the junctions with said guide columns, said tension member between the guide columns having an upper web extended laterally beyond the flanges with the ends continued diagonally upward and outward below but parallel to the upper edges of the diagonal end portions of said member.

In testimony whereof I affix my signature:
